UNITED STATES PATENT OFFICE

TADAHIRA D. KATAYAMA, OF SEATTLE, WASHINGTON.

SACK.

1,124,140.

Specification of Letters Patent.

Patented Jan. 5, 1915.

Application filed August 5, 1914. Serial No. 855,306.

To all whom it may concern:

Be it known that I, TADAHIRA D. KATAYAMA, a subject of the Emperor of Japan, residing at Seattle, in the county of King 5 and State of Washington, have invented certain new and useful Improvements in Sacks; and I do hereby declare the following to be a full, clear, and exact description of the invention, such as will enable others 10 skilled in the art to which it appertains to make and use the same.

My invention relates to a form of sack and construction thereof, to be used in ordinary grocery and market shops, and elsewhere, 15 when it is desirable to keep a number of folded sacks the top or front one of which may be quickly opened for use without the insertion therein of the hands or other unsanitary means, and the said opening to be accomplished by the simple movements required to bring the sack into proper 20 position to be filled.

Figure 1 is a front view of the sack folded, mouth down. Fig. 2, is side view of the 25 sack folded and suspended, mouth down. Fig. 3, is a front view of the sack opened; mouth down. Fig. 4, is a side view of the sack opened, bottom down.

Referring to the drawings, A, represents 30 a point near the mouth of sack about where the operator would grasp the sack to open it; a, and b, represent the folded edges of the sides of the sack.

C, represents the inside mouth of sack as 35 it is opened; D, represents the entire bottom portion of the sack.

D' represents a flap attached to the bottom either as a separate piece connected thereto or as an extension of one side portion 40 of the sack. The lower ends or portion of the sack are folded down or inward and pasted, the portions folded into quarters or sections shown by e, f, p, and q. Near the outer end of flap D' is a hole o, at a point 45 beyond the outer line of the sack when folded, and d represents a perforated line across the base of flap D' at or near the point of its attachment to the bottom D.

E, represents the main body of the sack, 50 m represents a circle or the common trademark sign, placed at the point A, where the hands or fingers grasp sack; n, represents a nail or means for holding the sack passing through the hole o of flap D', and w, is a 55 wall or bracket for supporting the sacks.

To secure the quick and easy opening of the sack as described below, the flap D', is attached to the bottom D at a point not exactly at the transverse center of the latter, but rather between said center and the upper 60 fold line between the bottom and what would be the rear side as the sack hangs on the nail. The hole o is purposely made in the flap D' at such point that, when the flap lies against the folded bottom as shown in Fig. 1, the 65 hole will be beyond the contour of the bag-bottom; and this permits the nail n to pass through the hole without wrinkling the bag or disarranging the rectangular outline of its folded bottom. The result of this construction is that, when the sack is drawn 70 downward, the nail by preventing downward movement of the flap, tends to cause the upper and inner side of the bottom to move downward against the wall or the adjoining 75 sack.

In use the operator suspends any desired number of sacks upon a nail or hook, and as they may be required for separate use, he grasps the first sack at A, and gently draws 80 down the sack till the bottom portion of the sack (the bottom being upward) is at right angles to the wall of next sack, then by a quick jerk the sack is removed from the nail, either by the tearing off of the flap at d, or 85 by the nail tearing out the flap beyond o. As the mouth of the sack is then drawn in circular motion to reverse the position of the sack, the body is fully inflated, and ready 90 for filling with merchandise, etc. The sacks being suspended with mouths downward, prevents any dirt accumulating in the sacks, and as they are opened by the motion bringing them into position for use, there will be 95 no necessity for the merchant to use his hand, as is customary, to open the sack before filling.

Having fully described my invention, what I claim as my invention is,

1. The herein described sack having a bottom of rectangular outline and a suspending flap secured to said bottom on a line nearer one side of the sack than the other, the flap being of a length to project beyond the angle between the bottom and the nearest side, and said flap having an aperture near its outer end, for the purpose set forth. 105

2. The herein described sack having a bottom of rectangular outline and a suspending flap attached to said bottom on a line nearer 110

one side of the sack than the other, the flap being of a length to project beyond the angle between the bottom and the nearest side and having an aperture near its outer end and a transverse line of perforations near its point of attachment, for the purpose set forth.

In testimony whereof I affix my signature in presence of two witnesses.

TADAHIRA D. KATAYAMA.
